UNITED STATES PATENT OFFICE

ALBERT H. KENNEDY AND H. P. KENNEDY, OF BRUNSWICK, OHIO.

IMPROVEMENT IN CATTLE-POKES.

Specification forming part of Letters Patent No. **59,408**, dated November 6, 1866.

To all whom it may concern:

Be it known that we, ALBERT H. KENNEDY and H. P. KENNEDY, of Brunswick, in the county of Medina and State of Ohio, have invented a new and Improved Poke to prevent animals from jumping; and we do hereby declare that the following is a full, exact, and clear description of the construction and operation of the same, reference being had to the annexed drawings, making a part of this specification, in which—

Figure 1 is a view of the poke when in operation. Fig. 2 is the lower part of the bow *a*, Fig. 1, showing the slot *b*, Fig. 2, through which the spring *c* and pricks *d*, Fig. 1, pass when the poke is taken from the animal's neck. The pricks *d* are made to prick the neck when the animal comes in contact with the fence.

The stale *e* can be attached outside or inside of the bow *a*, in which a pin, *f*, made of wood or metal, is inserted to keep the stale *e* from falling back too far.

The roller *g* can be made of wood or metal, with the pricks *d* to pass by the roller.

The spring *c* can be made of any kind of wire that will answer the purpose.

The ends of bow *a* are secured by rivets *h*, to prevent their splitting.

The stale *e* is secured by rivet *i* on roller *j*, which connects the ends of bow *a* by inserting key *k* in the roller *j*.

Fig. 3 represents the stale when taken from the bow *a*, Fig. 1, without a slot.

We claim—

1. The improvement by having the pricks *d* stationary in the roller *j*, Fig. 1, which operate in the manner and for the purpose set forth.

2. The combination of the roller *g* with spring *ee*, as a guard over the pricks *d* when the poke is not in operation, by which the pricks *d* can pass, arranged and operating substantially as shown and described.

3. The slot *b*, through which the pricks *d* and springs *cc* can pass when the poke is removed from the animal, as described.

4. The placing of the stale *e* on the outside of bow *a* with a slot, *b*, and on the inside of bow *a* without a slot, and keys in both ends of roller *l*, as represented in Fig. 3, as shown and described.

5. The pin *f* in bow *a*, Fig. 1, to keep the stale *e* in its place, in the manner shown and described.

A. H. KENNEDY.
H. P. KENNEDY.
